UNITED STATES PATENT OFFICE.

JAMES H. BARRETT, OF BEGGS, OKLAHOMA.

GASKET CHECK VALVE.

Application filed April 5, 1923. Serial No. 630,124.

To all whom it may concern:

Be it known that I, JAMES H. BARRETT, a citizen of the United States, residing at Beggs, in the county of Okmulgee and State 5 of Oklahoma, have invented a new and useful Gasket Check Valve, of which the following is a specification.

This invention relates to water circulating systems for internal combustion engines, 10 and more particularly to check valves to be located therein.

The object of the invention is to provide a gasket carried check valve to be used in motors in which water is used to circulate 15 through the engine to prevent overheating, said valve being so constructed and located as to insure the circulation of the water and prevent back pressure due to steam.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed may be made within the scope of what is claimed without departing from the spirit of the invention.

In the accompanying drawings:—

30 Fig. 1 represents a perspective view of a Ford car engine equipped with this improvement.

Fig. 2 is a front elevation of the gasket embodying the invention

35 Fig. 3 is an enlarged detail sectional view taken on the line 3—3 of Fig. 1.

Ford motors are received from the factory with no checks between the motor and the radiator and consequently water from 40 the radiator does not circulate through the motor at all times, but is frequently forced back into the radiator from the bottom by steam pressure from the motor. This results in the boiling of the water and over- 45 heating of the engine. This invention is designed to be installed in the inlet between the water jacket of the motor and the radiator whereby the water is forced back into the radiator from the top of the motor. 50 This prevents overheating of the motor and in freezing weather is an aid to prevent the water freezing in the radiator since the water always freezes in the bottom of the radiator first and by causing this water at

the bottom of the radiator to continuously 55 circulate, the freezing is prevented.

In the accompanying drawings, an engine 1 such as is ordinarily used in Ford cars is shown having the usual water jacket 2 connected by a coupling 3 at the front portion thereof with the radiator 5 while a return pipe 4 connects the bottom of the radiator with the water jacket at the side of the engine. 60

The gasket 10 which constitutes this invention is located between the coupling 3 and the front end of the water jacket and is constructed in detail as shown clearly in Fig. 2 comprising the usual copper plates 65 having a suitable filler between them and which are provided in their ends with apertures 11 to receive the bolts which connect the coupling with the water jacket. 70

This gasket 10 has the usual opening 12 therein here shown surrounded by a seat 75 13 having mounted thereon a flap valve 14. This valve 14 is hingedly connected as shown at 15 and has an opening 14^a at a point diametrically opposite the hinged portion, the size of which is adjusted by means 80 of a rotatable plate 16 here shown in the form of a disk journaled centrally at 17 to the valve.

This plate 16 is equipped with a finger grip 85 in the form of a lug 18 to facilitate its rotation and has a plurality of apertures 19 and 19^a to vary the size of the opening in the valve which opening is designed to permit water to drain from the radiator into the engine jacket when desired. 90

This valve is mounted to swing outwardly toward the radiator so that the water in the engine will be forced out through the radiator and prevented from flowing back should steam be generated. 95

Another one of these check carried gaskets is shown at 20 located between the inner end of the pipe 4 and water jacket of the engine and opens inwardly, permitting the water to flow from pipe 4 into the water jacket of the engine and prevents its return, thus insuring a continuous circulation 100 of the cooling fluid and preventing steam from entering pipe 4 from the engine water jacket. 105

Various changes in the form, shape, proportion and other minor details of construction may be made without departing from

the principle or sacrificing any of the advantages of the claimed invention.

I claim:—

The combination with an engine having a water jacket and radiator, a coupling between said radiator and jacket at the top of the engine and a pipe connecting the lower portion of the radiator with said

water jacket; of gasket carried check valves located between said coupling and jacket and supply pipe and jacket, the valves in said gaskets opening in the same direction. 10

In testimony that I claim the foregoing as my own, I have heretofore affixed my signature.

JAMES H. BARRETT.
